TRAFFIC SIGNALING SYSTEM

Thomas Ashton Logan, Chicago, Ill., assignor to
Associated Electric Laboratories, Inc., Chicago,
Ill., a corporation of Delaware

Application February 12, 1938, Serial No. 190,201

10 Claims. (Cl. 246—130)

The present invention relates to traffic signaling systems, and more particularly to improvements in railway and highway traffic signaling systems, wherein a traffic signal device located near an intersection of a railway track and a highway is controlled by apparatus responsive to the condition of a stretch of railway track adjacent the intersection.

In signaling systems of the character noted, the traffic signal device located near the intersection usually comprises two groups of traffic signals positioned to face the opposite highway approaches and two groups of traffic signals positioned to face the opposite railway approaches. Usually the group of traffic signals positioned to face each highway approach comprises clear, caution and danger signal lamps and the group of traffic signals positioned to face each railway approach comprises caution and danger signal lamps; thereby presenting to the highway and the railway approaches universally recognized indications. The apparatus responsive to the condition of the stretch of railway track adjacent the intersection is so arranged that the traffic signal device is controlled to present traffic signals to the highway and the railway approaches in a predetermined sequence as trains are moved with respect to this stretch of railway track.

In a signaling system of the type described it is desirable that the traffic signal device present traffic signals to the highway and the railway approaches in the following sequence. Clear signals should be presented to the highway approaches and danger signals presented to the railway approaches when the stretch of railway track adjacent the intersection is clear of trains. Clear and caution signals should be presented to the highway approaches and danger signals presented to the railway approaches when a train enters this stretch of railway track. The caution signals presented to the highway approaches should be extinguished and danger signals presented to the highway approaches and caution signals presented to the railway approaches a predetermined time interval after the train enters this stretch of railway track. The danger signals presented to the highway approaches and the caution signals presented to the railway approaches should be extinguished and clear signals presented to the highway approaches and danger signals presented to the railway approaches after the train leaves this stretch of railway track provided the same is clear of other trains. It is extremely important that the traffic signal device

presents traffic signals to the highway and the railway approaches in the sequence set forth above in order to prevent the presentation of confusing or erroneous indications to the highway approaches of the condition of the stretch of railway track adjacent the intersection. While prior traffic signaling systems embodying apparatus responsive to the condition of a stretch of railway track adjacent a highway intersection for controlling the operation of a traffic signal device of this type in the manner described above are known, the apparatus involved is quite complicated in character and expensive to manufacture and install. Moreover, such apparatus is impossible in operation and must be frequently inspected and adjusted in order to control the traffic signal device to present the traffic signals to the highway and the railway approaches in the desired predetermined sequence.

It is an object of the present invention, therefore, to provide an improved traffic signaling system of the character briefly described above, which is of simple and economical construction, and which operates in a thoroughly reliable manner to present traffic signals to the highway and the railway approaches in the above-mentioned sequence.

It is another object of the invention to provide in a traffic signaling system of the character noted, improved and exceedingly simple apparatus which is controlled in accordance with the condition of the stretch of railway track adjacent the intersection and which is connected and arranged to control the traffic signal device in a manner such that it is impossible for the latter to present confusing traffic signals or depart from a predetermined sequence of presenting traffic signals to the highway and the railway approaches.

It is a further and more specific object of the invention to provide a traffic signaling system of the character described wherein improved and exceedingly simple circuit arrangements are employed for controlling the traffic signal device to present traffic signals to the highway approaches in a predetermined sequence.

In general, the objects as set forth above are attained in accordance with the present invention by providing in a traffic signaling system of the character described, a control device operable between a normal position and an off-normal position, and apparatus whereby the control device positively controls the operation of the clear and danger highway signals and the caution and danger railway signals of the traffic

signal device. The apparatus is so arranged that the clear highway signal and the danger railway signal are rendered active and the danger highway signal and the caution railway signal are rendered inactive, when the control device is operated to its normal position; and that the danger highway signal and the caution railway signal are rendered active and the clear highway signal and the danger railway signal are rendered inactive, when the control device is operated to its off-normal position. Also, this apparatus includes a timer, means operated when a train approaches the intersection for rendering the caution highway signal of the traffic signal device active and for setting the timer into operation, control means operated by the timer for rendering the caution highway signal of the traffic signal device inactive and for operating the control device from its normal position to its off-normal position, and additional means for positively insuring that the caution highway signal of the traffic signal device is rendered inactive substantially simultaneously with the operation of the control device from its normal position to its off-normal position.

The novel features believed to be characteristic of the invention are set forth with particularity in the appended claims. The invention, both as to its organization and method of operation, together with further objects and advantages thereof, will best be understood by reference to the specification taken in connection with the accompanying drawing in which the single figure illustrates a traffic signaling system having embodied therein the features of the present invention.

Referring now more particularly to the drawing, the traffic signaling system illustrated comprises a stretch of railway track 10 including track rails 10a and 10b, along which traffic normally moves from the left toward the right as indicated by the arrow. The railway track 10 is intersected by a highway 11, and a traffic signal device 12 is located at or near the intersection.

The traffic signal device 12 is provided with two sides 12H positioned to face the opposite highway approaches and one side 12R positioned to face the railway approach including the stretch of railway track 10. Although it is not essential, as it is assumed that traffic normally moves in the direction indicated by the arrow from the left toward the right, it is preferable that the traffic signal device 12 be provided with a side 12R positioned to face the opposite railway approach. Each side 12H of the traffic signal device 12 carries a group of three signal lamps 13, 14 and 15 arranged in vertical alignment, these lamps being green, amber and red, respectively, in order to present, when illuminated, corresponding clear, caution and danger signals to the highway approach. Each side 12R of the traffic signal device 12 carries a group of two signal lamps 16 and 17 arranged in vertical alignment, these lamps being amber and red, respectively, in order to present, when illuminated, corresponding caution and danger signals to the railway approach. The corresponding signal lamps of the corresponding groups are wired in multiple and provided with operating or energizing circuits adapted to be connected to a suitable source of A. C. supply. As shown in the diagrammatic layout illustrating one of the sides 12R and one of the sides 12H of the traffic signal device 12, one terminal of each of the signal lamps 13 to 17, inclusive, is connected to a common conductor C20 and the other terminal of each of these signal

lamps is connected, respectively, to conductors C21 to C25, inclusive.

The common conductor C20 is connected directly to one side of a source of A. C. supply while the conductors C21, C23, C24 and C25 are connected to the stationary contacts RC34, RC35, RC36 and RC37, respectively, of a control device or switch 31. The switch 31 is provided with two armatures RA32 and RA33 which are operable together by a switch relay R30 from a normal position to an off-normal position. The armatures RA32 and RA33 are connected by way of a conductor C26 to the other side of the source of A. C. supply. In the switch 31 the armature RA32 controls the associated contacts RC34 and RC35, while the armature RA33 controls the associated contacts RC36 and RC37. When the switch 31 is operated to its normal position, the energizing circuits of the signal lamps 13 and 17 are completed at the armature RA32 and its associated contact RC34 and at the armature RA33 and its associated contact RC36 and RC37, respectively. The energizing circuit of the signal lamp 13 extends from one side of the source of A. C. supply by way of C20, the signal lamp 13, C21, RC34, RA32 and C26 to the other side of the source of A. C. supply; and the energizing circuit of the signal lamp 17 extends from one side of the source of A. C. supply by way of C20, the signal lamp 17, C25, RC37, RA33 and C26 to the other side of the source of A. C. supply. With the switch 31 in its normal position, the energizing circuits of the signal lamps 15 and 16 are interrupted at the armature RA32 and its associated contact RC35 and at the armature RA33 and its associated contact RC36, respectively. The energizing circuit of the signal lamp 15 extends from one side of the source of A. C. supply by way of C20, the signal lamp 15, C23, RC35, RA32 and C26 to the other side of the source of A. C. supply; and the energizing circuit of the signal lamp 16 extends from one side of the source of A. C. supply by way of C20, the signal lamp 16, C24, RC36, RA33 and C26 to the other side of the source of A. C. supply. With the switch 31 in its off-normal position the energizing circuits of the signal lamps 13 and 17 are interrupted at the armature RA32 and its associated contact RC34 and at the armature RA33 and its associated contact RC37, respectively.

Thus the signal lamps 13, 15, 16 and 17 are controlled by the switch 31 in a manner such that when the clear highway signal lamp 13 and the danger railway signal lamp 17 are rendered active, the danger highway signal lamp 15 and the caution railway signal lamp 16 are rendered inactive; and that when the danger highway signal lamp 15 and the caution railway signal lamp 16 are rendered active, the clear highway signal lamp 13 and the danger railway signal lamp 17 are rendered inactive. This arrangement positively prevents the signal lamps controlled by the switch 31 from being operated to present confusing traffic signals to the highway and the railway approaches.

The ends of the track rails 10a and 10b are separated from the ends of the adjoining rails by suitable insulated joints 9 in order to provide a track section 10s in the stretch of railway track 10, the track section 10s being electrically 75

insulated from the remainder of the railway track. The track section 10s is provided with a track circuit comprising a battery 18 and a track relay R40, the track relay R40 being normally energized from the battery 18 when the track section 10s is clear of trains, and being short-circuited and deenergized when the track section 10s is occupied by a train.

Apparatus responsive to the condition of the track section 10s for operating the traffic signal device 12 is provided, which includes the track relay R40; a slave relay R50; a vibratory or pendulum type relay R60, having a weighted armature RA61 adapted to vibrate for a predetermined time interval between two spaced-apart contacts RC62 and RC63 when the vibratory relay R60 is deenergized; a slow-to-release relay R70; and the switch relay R30. The slave relay R50 is provided with an energizing circuit extending from the positive terminal of a battery, not shown, by way of the armature RA41 of the track relay R40 and the winding of R50 to the negative terminal of battery. The vibratory relay R60 is provided with an energizing circuit extending from the positive terminal of battery by way of the armature RA52 of the slave relay R50 and the winding of R60 to the negative terminal of battery. The slow-to-release relay R70 is provided with a primary energizing circuit extending from the positive terminal of battery by way of the armature RA51 of the slave relay R50 and the winding of R70 to the negative terminal of battery; and a secondary energizing circuit extending from the positive terminal of battery by way of the weighted armature RA61 of the vibratory relay R60, the associated contact RC62 or RC63, the armature RA71 of the relay R70 and the winding of R70 to the negative terminal of battery. The switch relay R30 is provided with an energizing circuit extending from the positive terminal of battery by way of the armature RA72 of the slow-to-release relay R70 and the winding of R30 to the negative terminal of battery.

45 The caution highway signal lamp 14 is provided with an energizing circuit extending from one side of the source of A. C. supply by way of C20, the signal lamp 14, C22, the armature RA13 of the slow-to-release relay R70, the armature RA53 of the slave relay R50 and a conductor C21, to the other side of the source of A. C. supply. Thus 50 the energizing circuit of the caution highway signal lamp 14 is controlled by the slow-to-release relay R70 and the slave relay R50. The vibratory relay R69 and the slow-to-release relay R70 55 constitute a timer for controlling the operation of the traffic signal device 12.

Considering the operation of the traffic signaling system illustrated, it will be observed that the energizing circuit of the vibratory relay R60 and the primary energizing circuit of the slow-to-release relay R70 are normally completed at RA52 and RA51, respectively, of the slave relay R50, which latter relay is controlled by the track relay R40. The secondary energizing circuit of the slow-to-release relay R70 is normally completed at RA61 and the associated contact RS62 of the vibratory relay R60 and at RA71 of the relay R70, thereby maintaining the switch relay R30 operated, which latter relay retains the switch 31 operated to its normal or operated position. When a train enters the track section 10s, the winding of the track relay R40 is short-circuited or deenergized, causing the track relay R40 to restore and interrupt at RA41 the energizing circuit of the slave relay R50. The slave relay R50

then restores and interrupts at RA52 and RA51, respectively, the energizing circuit of the vibratory relay R60 and the primary energizing circuit of the slow-to-release relay R70. The vibratory relay R60 then releases its weighted armature RA61, which vibrates between the associated contacts RC62 and RC63, thereby intermittently completing and interrupting the secondary energizing circuit of the relay R10. The relay R10, being of the slow-to-release type, does not restore as long as its secondary energizing circuit is intermittently completed by the vibrating armature RA61 of the vibratory relay R60. However, after a predetermined time interval the armature RA61 of the vibratory relay R60 assumes an intermediate position between the associated contacts RC62 and RC63, thereby completely interrupting the secondary energizing circuit of the slow-to-release relay R70. Shortly thereafter, the slow-to-release relay R70 restores and interrupts at RA71 a further point in its secondary energizing circuit, and interrupts at RA72 the energizing circuit of the switch relay R30. The latter relay then restores, thereby operating the switch 31 to its off-normal position. The time interval during which the secondary energizing circuit of the slow-to-release relay R70 is intermittently completed and interrupted depends upon the characteristic of the weighted armature RA61 of the vibratory relay R60, and may be varied between predetermined limits by adjusting the position of the weight carried by the armature RA61. Thus, the time interval between the time a train enters the track section 10s and the time the switch 31 is operated from its normal position to its off-normal position to control the traffic signal device 12, may be conveniently adjusted within predetermined limits.

adjusted within predetermined limits.

Also, it will be observed that when the slave relay R50 restores, upon the entrance of a train into the track section 10s, it completes at RA53 the energizing circuit of the caution highway signal lamp 14 to render this signal lamp active. The caution highway signal lamp 14 remains active until the slow-to-release relay R70 restores, a predetermined time interval after the train enters the track section 10s, and interrupts at RA73 the energizing circuit of this signal lamp to render the same inactive. Furthermore, it will be seen that the caution highway signal lamp 14 is rendered inactive at substantially the same time the switch 31 is operated by the switch relay R30 from its normal position to its off-normal position to control the signal lamps 13, 15, 16 and 17 in the traffic signal device 12. This arrangement positively prevents the signal device 12 from presenting confusing traffic signals to the highway and the railway approaches.

Referring now more specifically to the operation of the traffic signaling system illustrated and assuming that the track section 10s is clear of trains, the above-traced energizing circuits of the track relay R40, the slave relay R50, the vibratory relay R60, the slow-to-release relay R10, and the switch relay R30 are completed and these relays are operated. Under this condition of the track section 10s, the energizing circuit of the caution highway signal lamp 14 is interrupted at RA53 of the slave relay R50, and the switch 31 is operated to its normal position by the switch relay R30. The switch 31 completes at RA32 and the associated contact RC34 the energizing circuit of the clear highway signal lamp 13, and completes at RA33 and the associated contact RC37 the energizing circuit of the danger railway signal lamp 11. 70 75

The traffic signal device 12 thus presents clear traffic signals to the opposite highway approaches and danger traffic signals to the opposite railway approaches. These traffic signals indicate to one using the highway that the stretch of railway track adjacent the intersection is clear of trains and that it is safe to enter the intersection.

When a train enters the track section 10, the track relay R40 is short-circuited and restores. Upon restoring, the track relay R40 interrupts at RA41 the energizing circuit of the slave relay R50. The latter relay then restores and interrupts at RA51 the primary energizing circuit of the slow-to-release relay R70, and interrupts at RA52 the energizing circuit of the vibratory relay R60. Also, the slave relay R50 completes at RA53 the energizing circuit of the caution highway signal lamp 14. At this time the traffic signal device 12 presents clear and caution traffic signals to the opposite highway approaches and danger signals to the opposite railway approaches. These traffic signals indicate to one using the highway that a train has entered the stretch of track adjacent the intersection and that soon the train will enter the intersection. Also, these traffic signals indicate to the engineer that the traffic signal device 12 has not operated to indicate to one using the highway that it is imminently dangerous to enter the intersection. When the vibratory relay R60 is deenergized, the weighted armature RA61 is released and begins to vibrate between the associated contacts RC62 and RC63, thereby completing and interrupting intermittently the secondary energizing circuit of the slow-to-release relay R70 to retain the latter relay operated. After a predetermined time interval, depending upon the setting of the weighted armature RA61, weighted armature RA61 assumes an intermediate position between the associated contacts RC62 and RC63, thereby completely interrupting the secondary energizing circuit of the slow-to-release relay R70. A short time thereafter the slow-to-release relay R70 restores and interrupts at RA71 a further point in its secondary energizing circuit. Also, the slow-to-release relay R70 interrupts at RA72 the energizing circuit of the switch relay R30, and interrupts at RA73 the energizing circuit of the caution highway signal lamp 14. The switch relay R30 then restores, and substantially simultaneously the caution highway signal lamp 14 is extinguished. Upon restoring, the switch relay R30 causes the switch 31 to operate from its normal position to its off-normal position. When the switch 31 is operated from its normal position, it interrupts at RA32 and the associated contact RC34 the energizing circuit of the clear highway signal lamp 13, and interrupts at RA33 and the associated contact RC37 the energizing circuit of the danger railway signal lamp 17. When the switch 31 is operated to its off-normal position, it completes at RA32 and the associated contact RC35 the energizing circuit of the danger highway signal lamp 15, and completes at RA33 and the associated contact RC36 the energizing circuit of the caution railway signal lamp 16. At this time the traffic signal device 12 presents danger traffic signals to the opposite highway approaches and caution traffic signals to the opposite railway approaches. These traffic signals indicate to one using the highway that a train has entered the stretch of track adjacent the intersection and that it is imminently dangerous to enter the intersection. Also, these traffic signals indicate to the engineer that the traffic signal device 12 has oper-

ated to indicate to one using the highway that it is imminently dangerous to enter the intersection.

When the train leaves the track section 10s, the track relay R40 is energized, provided, of course, this track section is clear of other trains. The track relay R40 operates and completes at RA41 the energizing circuit of the slave relay R50. The latter relay operates and completes at RA51 the primary energizing circuit of the slow-to-release relay R70, and completes at RA52 the energizing circuit of the vibratory relay R60. Also, the relay R50 interrupts at RA53 a point in the energizing circuit of the caution highway signal lamp 14. The vibratory relay R60 operates and prepares at RA61 and the associated contact RC62 a point in the secondary energizing circuit of the slow-to-release relay R70. The latter relay also operates and completes at RA71 its secondary energizing circuit, and completes at RA72 the energizing circuit of the switch relay R30. The slow-to-release relay R70 also prepares at RA73 a point in the energizing circuit of the caution highway signal lamp 14. Upon operating, the switch relay R30 operates the switch 31 from its off-normal position back to its normal position. The switch 31, upon operating from its off-normal position, interrupts at RA32 and the associated contact RC35 the energizing circuit of the danger highway signal lamp 15, and interrupts at RA33 and the associated contact RC36 the energizing circuit of the caution railway signal lamp 16. The switch 31, upon operating to its normal position, completes at RA32 and the associated contact RC34 the energizing circuit of the clear highway signal lamp 13, and completes at RA33 and the associated contact RC37 the energizing circuit of the danger railway signal lamp 17. The traffic signal device 12 then again presents clear traffic signals to the opposite highway approaches and danger traffic signals to the opposite railway approaches. These traffic signals indicate to one using the highway that the stretch of railway track adjacent the intersection is again clear of trains and that it is safe to enter the intersection.

From the foregoing description of the traffic signaling system it will be apparent that the signal device located near the intersection of the railway track and the highway is controlled by the apparatus responsive to the condition of the stretch of the railway track adjacent the intersection in a simple manner to present traffic signals to the highway and railway approaches in a predetermined sequence. Moreover, the control apparatus is so arranged that it is impossible for the signal device to present confusing traffic signals to these approaches or depart from the predetermined sequence of presenting traffic signals.

While there has been described what is at present considered to be the preferred embodiment of the invention, it will be understood that various modifications may be made therein without departing from the invention, and it is intended in the appended claims to cover all such modifications as fall within the true spirit and scope of the invention.

What is claimed is:

1. A traffic signaling system comprising a stretch of railway track intersected by a highway, clear and caution and danger signals located near the intersection, a device operable between a first position and a second position, apparatus whereby said device controls the op-

eration of said clear and said danger signals, said apparatus being so arranged that said clear signal is rendered active and said danger signal is rendered inactive when said device is operated 5 to said first position and said danger signal is rendered active and said clear signal is rendered inactive when said device is operated to said second position, a timer, means operated when a train approaches the intersection for rendering 10 said caution signal active and for setting said timer into operation, and means controlled by said timer for rendering said caution signal inactive and for causing said device to operate from said first position to said second position.

15 2. A traffic signaling system comprising a stretch of railway track intersected by a highway, clear and caution and danger signals located near the intersection, a device operable between a normal position and an off-normal position, apparatus whereby said device controls the operation of said clear and said danger signals, said apparatus being so arranged that said clear signal is rendered active and said danger signal is rendered inactive when said device is operated 20 to its normal position and said danger signal is rendered active and said clear signal is rendered inactive when said device is operated to its off-normal position, means including a relay for operating said device, means operated 25 when a train approaches the intersection for rendering said caution signal active and for conditioning said relay to operate after a predetermined time interval, and means responsive to the operation of said relay for rendering said 30 caution signal inactive and for causing said device to operate from its normal position to its off-normal position.

35 3. A traffic signaling system comprising a stretch of railway track intersected by a highway, clear and caution and danger signals located 40 near the intersection, a device operable between a normal position and an off-normal position, apparatus whereby said device controls the operation of said clear and said danger signals, said apparatus being so arranged that said clear signal is rendered active and said danger signal is rendered inactive when said device is operated to its normal position and said danger signal is rendered active and said clear signal is rendered 45 inactive when said device is operated to its off-normal position, means including a slow-to-release relay for operating said device, an energizing circuit for said slow-to-release relay, means operated 50 when a train approaches the intersection for rendering said caution signal active and for interrupting the energizing circuit of said slow-to-release relay, and means responsive to the restoration of said slow-to-release relay for rendering said caution signal inactive and for causing 55 said device to operate from its normal position to its off-normal position.

60 4. A traffic signaling system comprising a stretch of railway track intersected by a highway, clear and caution and danger signals located near 65 the intersection, a device operable between a normal position and an off-normal position, apparatus whereby said device controls the operation of said clear and said danger signals, said apparatus being so arranged that said clear signal is rendered active and said danger signal is rendered inactive when said device is operated to its normal position and said danger signal is rendered active and said clear signal is rendered inactive when said device is operated to its off-normal 70 position, means including a slow-to-release 75

relay for operating said device, primary and secondary circuits for energizing said slow-to-release relay, a vibratory relay, means operated when a train approaches the intersection for rendering said caution signal active, for interrupting the 5 primary energizing circuit of said slow-to-release relay and for controlling said vibratory relay, means including said vibratory relay for intermittently completing the secondary energizing circuit of said slow-to-release relay to retain said 10 slow-to-release relay operated during a predetermined time interval, and means responsive to the restoration of said slow-to-release relay for rendering said caution signal inactive and for causing said device to operate from its normal 15 position to its off-normal position.

15 5. A traffic signaling system comprising a stretch of railway track intersected by a highway clear and caution and danger signals located near the intersection, operating circuits for said signals, means including a switch operable between a first position and a second position for controlling the operating circuits of said clear and said danger signals, said switch being so connected and arranged that said clear signal is 20 rendered active and said danger signal is rendered inactive when said switch is operated to said first position and said danger signal is rendered active and said clear signal is rendered inactive when said switch is operated to said second position, a timer, means operated when a train approaches the intersection for rendering said caution signal active and for setting said timer into 25 operation, and means controlled by said timer for rendering said caution signal inactive and for causing said switch to operate from said first 30 position to said second position.

35 6. A traffic signaling system comprising a stretch of railway track intersected by a highway, clear and caution and danger signals located near 40 the intersection, circuits for energizing said signals, means including a switch operable between a normal position and an off-normal position for controlling the energizing circuits of said clear and said danger signals, said switch being connected and arranged to complete the energizing 45 circuit of said clear signal and to interrupt the energizing circuit of said danger signal when said switch is operated to its normal position and to complete the energizing circuit of said danger 50 signal and to interrupt the energizing circuit of said clear signal when said switch is operated to its off-normal position, a timer, means operated 55 when a train approaches the intersection for completing the energizing circuit of said caution signal and for setting said timer into operation, and means controlled by said timer for interrupting the energizing circuit of said caution signal and for causing said switch to operate from its 60 normal position to its off-normal position.

65 7. A traffic signaling system comprising a stretch of railway track intersected by a highway, clear and caution and danger highway signals located near the intersection, caution and danger railway signals located near the intersection, a device operable between a first position and a second position, apparatus whereby said device controls the operation of said clear and said danger highway signals and said caution and said danger railway signals, said apparatus being so 70 arranged that said clear highway signal and said danger railway signal are rendered active and said danger highway signal and said caution railway signal are rendered inactive when said device is operated to said first position and said 75

danger highway signal and said caution railway signal are rendered active and said clear highway signal and said danger railway signal are rendered inactive when said device is operated to said second position, a timer, means operated when a train approaches the intersection for rendering said caution highway signal active and for setting said timer into operation, and means controlled by said timer for rendering said caution highway signal inactive and for causing said device to operate from said first position to said second position.

8. A traffic signaling system comprising a stretch of railway track intersected by a highway, clear and caution and danger signals located near the intersection, a device operable between a normal position and an off-normal position, apparatus whereby said device controls the operation of said clear and said danger signals, said apparatus being so arranged that said clear signal is rendered active and said danger signal is rendered inactive when said device is operated to its normal position and said danger signal is rendered active and said clear signal is rendered inactive when said device is operated to its off-normal position, means including a slow-to-release relay for causing the operation of said device to its normal position, primary and secondary circuits for energizing said slow-to-release relay, a vibratory relay having an armature adapted to vibrate for a predetermined time interval after it is set into operation, means operated when a train approaches the intersection for rendering said caution signal active for interrupting the primary energizing circuit of said slow-to-release relay and for controlling the operation of said vibratory relay to set said armature into operation, means including contacts controlled by the vibration of said armature for intermittently completing the secondary energizing circuit of said slow-to-release relay during a predetermined time interval, thereby to retain said slow-to-release relay operated during said predetermined time interval, and means responsive to the restoration of said slow-to-release relay for rendering said caution signal inactive and for causing said device to operate from its normal position to its off-normal position.

9. A traffic signaling system comprising a stretch of railway track intersected by a highway, clear and caution and danger signals located near the intersection, a device operable

between a normal position and an off-normal position, apparatus whereby said device controls the operation of said clear and said danger signals, said apparatus being so arranged that said clear signal is rendered active and said danger signal is rendered inactive when said device is operated to its normal position and said danger signal is rendered active and said clear signal is rendered inactive when said device is operated to its off-normal position, a timer, means operated when a train enters said stretch of railway track for rendering said caution signal active and for setting said timer into operation, means including a relay for controlling the operation of said device, a circuit for energizing said relay, and means operated by said timer for rendering said caution signal inactive and for controlling the energizing circuit of said relay to cause said device to operate from its normal position to its off-normal position, said last-mentioned means being operated when the train leaves said stretch of track to control the energizing circuit of said relay to cause said device to operate from its off-normal position back to its normal position.

10. A traffic signaling system comprising a stretch of railway track intersected by a highway, clear and caution and danger signals located near the intersection, a device operable between a normal position and an off-normal position, apparatus whereby said device controls the operation of said clear and said danger signals, said apparatus being so arranged that said clear signal is rendered active and said danger signal is rendered inactive when said device is operated to its normal position and said danger signal is rendered active and said clear signal is rendered inactive when said device is operated to its off-normal position, a timer, means operated when a train enters said stretch of railway track for rendering said caution signal active and for setting said timer into operation, and control means operated by said timer for rendering said caution signal inactive and for causing said device to operate from its normal position to its off-normal position, said first-mentioned means being operated when the train leaves said stretch of railway track for reconditioning said timer for operation, said control means being operated when said timer is reconditioned to cause said device to operate from its off-normal position back to its normal position.
